KEYBOARD TAPE-PERFORATOR.

1,085,985.

Specification of Letters Patent.

Patented Feb. 3, 1914.

Application filed March 20, 1912. Serial No. 685,013.

To all whom it may concern:

Be it known that I, EDWARD E. KLEINSCHMIDT, a citizen of the United States, residing at New York city, borough of Manhattan, in the county of New York and State of New York, have invented certain new and useful Improvements in Keyboard Tape-Perforators, of which the following is a specification.

10 My invention relates to an apparatus for perforating tape by means of punches operated in combinations or groups, and controlled by selector keys, one for each combination or group, the perforated tape being 15 adapted for use in a Wheatstone or any other telegraph transmitter.

In my application, Serial No. 549,492, filed March 15th, 1910, I have described an apparatus comprising a key board selective 20 mechanism adapted to set groups of punch controllers, of various arrangements and numbers, corresponding to or representing the letters or other symbols on the key board; and means for actuating the controllers, and through them the punches, for 25 perforating a strip of paper to produce the electrical signal equivalents of the key board characters.

The present invention embodies substantially the same principle of operation of the 30 punches and has for its object to simplify and improve the construction of the selective mechanism, punch controllers, punches and the variable feed mechanism.

35 My invention will be understood from the following description taken in connection with the accompanying drawings in which—

Figure 1 is a plan view of the perforator with the casing broken away; Fig. 2, a side 40 elevation; Fig. 3, a transverse section through the key board on the plane of the line 3—3 of Fig. 2; Fig. 4, a horizontal section on the plane of the line 4—4 of Fig. 3; Fig. 5, a vertical section showing the 45 selectors and their connections with the key board; Fig. 6, a detail view of a solenoid for operating the main lever; Fig. 7, a plan view of the perforator mechanism with the 50 casing removed; Fig. 8, a detail view of the variable feed mechanism; Fig. 9, a detail view of the paper reel and control therefor; and Fig. 10, a detail view of the comb for restoring the punches to normal position.

Similar reference numerals indicate similar parts in the several views. 55

The perforating apparatus herein described, comprises (1) a key board selector mechanism; (2) perforating mechanism; (3) a variable feed mechanism; and (4) a paper control. I will describe these several 60 parts in the order above given.

The key board selector mechanism.—The purpose of this part of my apparatus is to position what I term "punch controllers," these controllers being adapted to be moved 65 into the path of a platen, or a punch head, to engage the corresponding punch to perforate the tape. It comprises a bank of key bars 1, the keys of which are provided with the characters of a universal key board, and the latter includes an additional bar for extra spacing between messages. All of the key bars are fulcrumed near their inner ends on a fixed transverse bar 2. Arranged longitudinally of and beneath the key bars, 70 are notched bars 3 fulcrumed near their inner ends on a transverse bar 4, and retained in their normal positions, in contact with the under edges of the corresponding key bars by springs 5 fixed at one end to the 75 base of the frame. Secured upon opposite sides of each key bar are small guide plates 6, and between said plates the notched bars 3 rest to prevent sidewise movement, each bar 3 having a short projecting section on its 80 upper edge to pass between the guide plates 6, as shown in Figs. 2 and 3. A transversely extending stop 7 limits the downward movement of bars 3 when depressed by the key bars, and a stop 7' limits the upward movement of the key bars. 85

The purpose of providing a notched selector bar instead of notching the underside of the key bar, as in my former application, 90 is to provide for an equal extent of movement of the outer or key ends of the key bars. The key bars 1 have a common fulcrum 2, as above stated, and the guide plates 6 are placed on the key bars at varying distances according to the length of the key 95 bar. In Fig. 2 I have shown five projections on the bars 3, indicating the points of contact between the key bars and the notched selector bars. The point of connection shown at the extreme left corresponds to 100 the space bar, and the point of connection 105 to

at the extreme right corresponds to the keys of the uppermost row, that is, the shorter the key bar the nearer to the fulcrum 2 is the point of connection between the key bar and the notched selector bar.

5 The bars 3 are notched according to the code to be perforated and bear upon a series of T-bars 8 extending transversely of the notched bars and of the key bars, there being one of said T-bars for each punch controller, and a universal bar, shown in Fig. 3, which is adapted to be depressed when any one of the key bars is depressed. The T-bars are supported by parallel links 9 10 pivoted to the legs of said bars, the other ends of said links being pivoted on a bracket 15 secured to the frame.

15 One edge of the vertical legs of the T-bars 8 is notched to receive a connecting bar 11, only the first and last of said legs and bars being shown in Fig. 3. As shown in Figs. 2 and 5, these bars 11 alternate in length to facilitate assembling, and are fulcrumed near their inner ends either on the same bar 25 4 upon which the notched bars 3 are fulcrumed, or upon another bar in proximity to the bar so as to insure a substantially equal movement of the punch controllers. Slotted plates 13 (Fig. 3) receive the ends of the 30 T-bars 8 and guide them in their vertical movements when depressed by the notched selector bars 3, and when raised by the springs 12 attached to them beyond the connecting bar 4. By reason of the parallel 35 links 9, the T-bars 11 will always move in a vertical path by whichever notched bar 3 a given T-bar may be depressed, that is, there will be no tilting of a depressed T-bar when moved by the extreme notched bars.

40 By having a common fulcrum bar 4 for the selector bars 3 and the connecting bars 11, or by having the fulcrums in close proximity to each other, a substantially equal extent of movement of the outer ends 45 of the connecting bars 11 is insured, whether a given bar 11 is depressed by a T-bar 8 near to or removed from the fulcrum. That is, by reference to Figs. 3 and 4 it will be seen that each T-bar 8 is adapted to be depressed by all of the notched selector bars 3, and that when a given T-bar is depressed the corresponding connecting bar 11 will also be depressed. By providing a common fulcrum 4 the extent of movement of the 55 short arms of the bars 11 will be equal whether that bar be connected to the nearest or to the farthest T-bar. This equal movement of the short arms of the connecting bars 11 insures an equal movement of 60 all of the punch controllers.

The ultimate work performed by the selector mechanism is to position the punch controllers 14 and 15 connected to the inner ends of the connecting bars 11, as shown in 65 Fig. 5, and arranged in two rows, as shown

in Figs. 7 and 8, with the upper ends of the controllers 15 terminating below those of the row 14, there being a controller for each punch. The controllers comprise an adjustable link connection, as shown, for the purpose of properly positioning the upper ends of the controllers relatively to the punches. These punch controllers have a vertical movement through openings in a punch head 16 which will now be described.

70 *The perforating mechanism.*—The particular perforating mechanism shown by me, for purposes of illustration, is intended to perforate a tape to be used in a Wheatstone transmitter. As shown, the perforator comprises two rows of punches 17 and 18 there being ten in each row, it being understood of course that there may be as many punches as desired according to the code. Between the punches 17 and 18 is a third row 19 for 80 punching a center row of perforations adapted to be engaged by the teeth of a feed wheel, hereafter described. A bracket 20, secured to the main frame, is provided with guide holes for the reception of the punches 85 which slide freely therein. The punch head 16 is slidably supported in the gibs 21 and is normally held in its retracted position, shown in Fig. 5, by a spring 22, being held against stops 24 on the ends of the gibs.

90 A die-plate 23, supported on the bracket 20, is provided with holes through which the punches pass after perforating the tape, the bracket 20 being recessed to provide a space for the passage of the tape 24. The 100 normal position of the punch controllers and of the punches is shown in Fig. 5. When a key is depressed, a group of controllers is raised corresponding in number and arrangement to the code symbol of the key struck, so that their upper ends will contact with the punches when the punch head is brought forward.

95 To move the punch head forward I provide a solenoid 25 (Fig. 6) the core of 110 which has connected to it one arm of a bell crank lever 26 pivoted on the frame. The other arm of said lever is connected to the main operating lever 27, the latter being pivoted on the frame and held in its retracted position by a spring 28, (Fig. 7). Secured to lever 27 is a stud 29 which passes through an elongated slot 30 in the punch head 16 (Fig. 5). The solenoid 25 is included in a circuit having a normally open 115 contact 31. The lower member of this contact is connected to, but insulated from, a bar 32, similar to the bars 11, and controlled by a universal T-bar 8 (Figs. 3 and 4), so that when bar 32 is depressed the lower contact will be raised and the circuit closed, energizing solenoid 25. This occurs when any one of the key bars is depressed. The movement of the solenoid core rocks lever 26 120 and the resulting forward movement of the 125 punch head 16 is shown in Fig. 8.

punch head 16, through lever 27 and stud 29, forces those punch controllers 14 and 15, which have been raised, against the ends of the corresponding punches 17 and 18 to perforate the tape, there being as many punches operated as there are punch controllers raised. The punches pass through the paper and into the holes in the die-plate 23. When the depressed key is released, contact 31 is opened and solenoid 25 deenergized. Spring 22 will then retract the punch head, and spring 28 will restore the main operating lever 27 to its normal position. When the depressed key is released it is restored to its normal position by a spring 5 connected to the notched selector bar 3 depressed by the key bar; and the T-bars 8 which were depressed, are restored to their normal position by the springs 12 acting through the corresponding connecting bars 11. The movement of the connecting bars 11 will restore the raised punch controllers 14 and 15 to their normal position.

In addition to the punches 17 and 18, which make the character perforations, an additional row of punches 19 is located midway between the rows of punches 17 and 18. The punch head 16 is provided with a block 33 which impinges against the punches 19 upon every forward movement of the punch head for perforating a central row of holes adapted to engage a feed wheel, as will be presently described.

To retract the punches after they have been moved forward to perforate the tape I provide a comb 34, secured to the punch head. As shown in Fig. 5 each punch has fixed thereto a collar 35 which, when the punches are in their retracted position, rest against a stop 36. When the punches are advanced the comb 34 is advanced, and when the punch head is retracted, the comb 34 is retracted and carries with it those punches which have been advanced until the latter are restored to their normal position with their collars bearing against the stop 36.

The variable feed mechanism.—To adapt my apparatus for codes requiring varying numbers of perforations for the key board characters it is necessary that a variable feed be provided. For that purpose I connect with the main operating lever 27, a feed operating lever 37 pivoted on a stud 37', the connection being made by a pin 38 on lever 27 engaging a slot 39 in the lever 37, as shown in Fig. 7. The parts are so related to each other that the pin 38 will engage the rear wall of slot 39 when lever 27 is retracted, and after the punch head 16 has been retracted sufficiently to withdraw the punches from the perforations in the tape, to feed the tape. At its free end the lever 37 has pivoted thereto, a floating lever 40. The lever 40 is connected to a lever 41 by

a link 42, and lever 41 has pivoted thereto, a link 43, the latter having connected to it a pawl 44 pivoted on an arm 45 which is mounted on the stud of feed wheel 46. Pawl 44 is in the form of a bell crank, and has an extended arm 44' having its end turned down through a slot in arm 45. A spring 44" engages the turned down end of arm 44' so as to normally hold the toe of pawl 44 in engagement with the teeth of wheel 47. When the pawl is positioned for operating wheel 47, the turned down end of arm 44' strikes the rear wall of the slot in arm 45 and prevents the pawl being thrown too far away from wheel 47. The feed wheel is provided with teeth on its periphery which engage the center row of perforations on the tape to feed the latter forward an amount determined by the throw of pawl 44. The latter engages a ratchet wheel 47 fast to the feed wheel, and said wheel 47 is advanced on the return movement of the pawl, the extent of such movement being sufficient to feed the tape an amount equal to the length of the last group of perforations, varying as such lengths vary, and an additional amount to space the groups. This is effected as follows: When lever 37 is moved forward, lever 40 is also moved forward with its fulcrum on the pivotal connection with link 41 the upper end strikes the last one of the punch controllers 15 of the group raised by the selector mechanism.

As shown in Fig. 5, the punch controllers 15 are shorter than the controllers 14, and the latter are formed with a lateral projection 48 which projection passes through slots 49 (Fig. 8) when the corresponding controller is raised. The notched selector bars are so arranged in the present apparatus that one of the controllers 15, which operate the punches in making the lower row of perforations, is always the last of the group. That is, as arranged the tape feeds to the left and the groups are read from left to right so that for any given group there will always be a projection 48 raised through one of the slots 49 in the path of a nose 50 on lever 40. When the nose 50 contacts with the projection 48 on the last one of the controllers 15 of the group, then the lever 40 fulcrums on that projection and the continued forward movement of lever 37 moves the lower end of lever 40 to the left, and through that movement the pawl 44 is retracted, or moved to the right, and engages the teeth of wheel 47 when the former comes to rest. When the main operating lever 27 is moved forward, lever 37 starts on its forward movement slightly in advance of the forward movement of the punch head. This slight time interval permits the nose of lever 40 to reach its final position before a rack 51 on the punch head (Figs. 5 and 8) 125

reaches the end of its forward movement. The continued forward movement of the punch head causes the rack 51 to engage the pointed end 40' of lever 40 to lock the latter in position and to prevent its rebound. When solenoid 25 is deenergized and the punch head retracted, lever 40 is released from engagement with the rack 51 and nose 50 strikes a spring stop 52 which forms a fulcrum for lever 40, moving the lower end of said lever at its point of connection with link 42 to the right, and the continued rearward movement of lever 37 causes a forward movement of pawl 44 to feed the ratchet wheel 47 and thereby the feed wheel 46, until the pawl strikes a stop 53. A stop 54 limits the forward movement of lever 37. By proper adjustment of the stops 53 and 54 and proportioning the parts described, the tape is always fed an amount equal to the length of the group of perforations and any additional amount desired to space the groups.

As shown in Fig. 8, I provide a stop 55 with which the nose of lever 40 engages when the space bar of the key board is operated. From the foregoing description it will be seen that the farther the nose of lever 40 is moved to the left, the less will be the feed of the tape.

As shown in Fig. 7 I attach a spring 56 to lever 40 to slightly retard the lower end of lever 40 when it is moved forward and to insure that the upper end of said lever is moved forward first. I also provide a back lash pawl 57 for ratchet wheel 47.

To insure positive engagement of the teeth of feed wheel 46 with the center row of perforations on the tape, I provide a toothed roller 58 on one end of a lever 59 pivoted at its center. The teeth of roller 58 pass between the teeth on the feed wheel 46 and force the paper over the teeth of the latter. The lever 59 carries at its other end a pressure roll 60 in proximity to stripper 61. Lever 59 is pivoted on a spring-pressed lever 62 to hold the rollers 58 and 60 to their work.

As before stated the bracket 20 is recessed, as shown in Fig. 5, to provide a space for the passage of the tape back of the die 23. To confine the tape in this space I provide a cover 63 hinged to the bracket 20. When the tape is to be inserted the cover 63 is thrown back. When the cover is lowered the space provided for the tape is the width of the tape and the latter is therefore prevented from shifting out of place, thus insuring the proper alinement of the perforations. A chute 64 is provided (Fig. 2) to receive the punches which fall in a suitable receptacle 65.

The paper control.—In perforating machines of the character herein described, some provision must be made for proper de-

livery of the tape from the reel. In the present apparatus the roll of tape is supported on a reel 66 freely rotatable on a stud carried by a bracket 67. Rigidly secured to said bracket is an arm 68 to which is pivoted, at its free end, a swinging arm 69. On the free end of said arm is a roll 70 around which the tape passes from the reel to the perforator. Fixed to the arm 69 is a brake shoe 71 adapted to bear against the periphery of wheel 66 and held in normal engagement therewith by a spring 72. The intermittent rapid feed of the tape draws the arm 69 and the brake shoe 71 away from the reel and as the latter is delicately poised, the tape is unwound until there is slack in the tape when spring 72 causes the brake shoe to contact with the reel, and stop its rotation and prevent an undue amount of tape being unwound between the feeding movements.

As in my former application the selector mechanism is purely mechanical in its construction and operation, the punch selectors being operated by a system of levers. The only electrical means employed by me is the solenoid 25, adapted to move forward the main operating lever 27. The parts connected to and controlled by the movement of said lever are purely mechanical in construction and operation. This elimination of wiring systems, motors, clutches, etc., as heretofore employed, greatly simplifies the construction of this class of apparatus and renders unnecessary the employment of expert electricians to repair or put in order.

What I claim and desire to secure by Letters Patent of the United States, is:

1. In a perforating machine, a reciprocating punch head, a plurality of punches, a support independent of the punch head in which said punches are mounted to slide, punch controllers mounted to reciprocate in the punch head, a keyboard selector mechanism comprising key levers with direct connections to the controllers and adapted to set the controllers in groups corresponding to the characters on the keyboard, means for moving the punch head to cause the set controllers to engage and operate the corresponding punches, and means connected to the punch head for restoring the operated punches to normal position.

2. In a perforating machine, a reciprocating punch head, a plurality of punches, a support independent of the punch head in which said punches are mounted to slide, punch controllers mounted to reciprocate in the punch head, a keyboard selector mechanism comprising key levers with direct connections to the controllers and adapted to set the controllers in groups corresponding to the characters on the keyboard, means for moving the punch head to cause the set controllers to engage and operate the corresponding punches, and means connected to the punch head for restoring the operated punches to normal position.

responding punches, a fixed guide against which said punches are moved when in normal position, and means connected to and movable with the punch head on its return movement to restore the punches to normal position against said fixed guide.

3. In a perforating machine, a reciprocating punch head, a plurality of punches, a fixed support in which said punches are adapted to move independently, a die secured to said head, punch controllers mounted to reciprocate in the punch head, a key board selector mechanism comprising key levers with direct connections to the controllers and adapted to set the controllers in groups corresponding to the characters on the keyboard, means for moving the punch head to cause the set controllers to engage and operate the corresponding punches, and means through which the punches pass connected to the punch head and adapted to restore the punches to normal position upon the return movement of the punch head.

4. In a perforating machine, a reciprocating punch head, a plurality of horizontally disposed punches, a support independent of the punch head in which said punches are mounted to slide, punch controllers mounted to reciprocate vertically in the punch head, a keyboard selector mechanism comprising key levers with direct connections to the controllers and adapted to raise the controllers in groups corresponding to the characters on the keyboard to bring them opposite the ends of corresponding punches, and means for moving the punch head to cause the set controllers to engage and operate the corresponding punches.

5. In a perforating machine, a reciprocating punch head, a plurality of punches, a support independent of the punch head in which said punches are mounted to slide, punch controllers mounted to reciprocate in the punch head, a keyboard selector mechanism comprising key levers with direct connections to the controllers and adapted to set the controllers in groups corresponding to the characters on the keyboard, means for moving the punch head to cause the set controllers to engage and operate the corresponding punches, and means to insure a substantially equal extent movement of said controllers whenever key is operated.

6. A perforating machine comprising a plurality of punches, punch controllers to operate said punches in groups corresponding to the key board characters, a key board selector mechanism to set said controllers, said selector mechanism comprising pivoted notched bars, pivoted bars connected to said controllers and adapted to be operated when the notched bars are operated, the fulcrum of said notched and said connecting bars being substantially at the same point, where by the punch controllers are moved substan-

tially the same extent whichever key is operated.

7. A perforating machine comprising a plurality of punches, punch controllers to operate said punches in groups corresponding to the key board characters, a key board selector mechanism to set said controllers, said selector mechanism comprising key bars having a common fulcrum, notched bars adapted to be operated by the key bars and having a common fulcrum, and mechanism intermediate said notched bars and the controllers whereby the latter are moved an equal extent whichever key is operated.

8. A perforating machine comprising a plurality of punches, punch controllers to operate said punches in groups corresponding to the key board characters, a key board selector mechanism to set said controllers, said selector mechanism comprising key bars having a common fulcrum, notched bars having a common fulcrum near their inner ends and retained in normal position in contact with the under edges of the corresponding key bars, and mechanism intermediate said notched bars and said punch controllers whereby the latter are moved a substantially equal extent whichever key is operated.

9. A perforating machine comprising a plurality of punches, punch controllers to operate said punches in groups corresponding to the key board characters, a key board selector mechanism to set said controllers, said selector mechanism comprising key bars, notched bars arranged longitudinally of and beneath the key bars and retained in their normal position in contact with the key bars, guide plates between the key bars and the said notched bars to prevent side-wise movement of the latter, and mechanism intermediate said notched bars and punch controllers whereby when a key bar is depressed the corresponding punch controllers will be set.

10. A perforating machine comprising a plurality of punches, punch controllers to operate said punches in groups corresponding to the key board characters, a key board selector mechanism to set said controllers, said selector mechanism comprising key bars, notched bars arranged longitudinally of and beneath the key bars, means for maintaining the notched bars in engagement with the key bars, the points of engagement being such that the shorter the key bar the nearer to the fulcrum of the latter is the point of engagement between a key bar and the corresponding notched bar.

11. A perforating machine comprising a plurality of punches, punch controllers to operate said punches in groups corresponding to the key board characters, a key board selector mechanism to set said controllers, said selector mechanism comprising key bars

130

- having a common fulcrum; notched bars arranged longitudinally of and beneath the key bars and having a common fulcrum, a series of bars extending transversely of the 5 notched bars, and a fourth series of bars connected to said transverse bars and having substantially the same fulcrum as the said notched bars, said fourth series of bars being connected to the said controllers.
- 10 12. A perforating machine comprising a plurality of punches, punch controllers to operate said punches in groups corresponding to the key board characters, a key board selector mechanism to set said controllers, 15 said selector mechanism comprising pivoted key bars, pivoted notched bars adapted to be operated by the key bars, a series of vertically movable bars extending transversely of and adapted to be operated by the notched 20 bars, and a fourth series of bars connected to said transverse bars and to the said controllers, said fourth series of bars having substantially the same fulcrum as said notched bars.
- 25 13. A perforating machine comprising a plurality of punches, punch controllers to operate said punches in groups corresponding to the key board characters, a key board selector mechanism to set said controllers, 30 said selector mechanism comprising key bars, a series of vertically movable bars extending transversely of the key bars, there being one of said vertically movable bars for each punch controller and a universal bar adapted 35 to be depressed when any one of the key bars is depressed, and a series of bars connecting said vertically movable bars with the punch controllers.
14. A perforating machine comprising a plurality of punches, punch controllers to operate said punches in groups corresponding to the key board characters, a key board selector mechanism to set said controllers, 40 said selector mechanism comprising a series 45 of vertically movable bars adapted to be operated in groups when the keys of the key board are depressed, parallel links supporting said vertically movable bars, and a series of bars connecting said vertically movable bars with the punch controllers.
- 50 15. A perforating machine comprising a plurality of punches, punch controllers to operate said punches in groups corresponding to the key board characters, a key board selector mechanism to set said controllers, 55 said selector mechanism comprising notched bars, a series of vertically movable bars extending transversely of and adapted to be operated in groups by the notched bars, 60 parallel links supporting said vertically movable bars, and a series of bars connecting the vertically movable bars with the punch controllers, said connecting bars and said notched bars having substantially the same 65 fulcrum.
16. A perforating machine comprising a plurality of punches, punch controllers to operate said punches in groups corresponding to the key board characters, a key board selector mechanism to set said controllers, 70 said selector mechanism comprising a series of notched bars, a series of vertically movable T-bars extending transversely of and adapted to be operated in groups by the notched bars, supporting parallel links pivoted to the legs of said T-bars, and connecting bars between said T-bars and the punch controllers. 75
17. A perforating machine comprising a plurality of punches, a main operating lever, 80 a floating lever connected to and adapted to be operated by said main lever, a ratchet feed wheel, an actuating pawl therefor, and means connected to said floating lever for positioning said pawl, and for causing it to 85 advance said wheel upon the return movement of the main operating lever of the punches after the punches have been withdrawn from the tape. 90
18. A perforating machine comprising a plurality of punches, punch controllers and means for setting the latter in groups corresponding to the code to be perforated, a ratchet feed wheel, an actuating pawl therefor, a floating lever and mechanism connecting said lever with said pawl, and means for moving said floating lever so as to cause it to fulcrum on the last one of the group of punch controllers set by the selector mechanism to determine the extent of throw of 95 said pawl. 100
19. In a tape perforating machine, a reciprocating punch head, a plurality of punches and controllers therefor, a key-board selector mechanism comprising key levers with direct connections to the controllers and adapted to set the latter in groups corresponding to the characters on the keyboard, a ratchet feeding device for the tape, an actuating pawl therefor, means for setting the pawl for operation on the forward movement of the punches and for causing it to actuate the feeding device on the return movement of the punches after the latter have been withdrawn from the tape, and means to determine the extent of 105 the setting movement of the pawl by the punch controllers. 110
20. In a perforating machine in combination, a plurality of punches and controllers therefor, means for moving said controllers to cause the punches to perforate the tape comprising a main lever, a feeding mechanism for the tape comprising a floating lever, a lever between said main lever and floating lever and connected to the latter between its ends, said floating lever having one end connected to the feeding device, the other end acting on one of the set controllers as a stop to determine the amount of 115 120 125 130

feed of the tape, and means for operating said main lever.

21. In a perforating machine in combination, a plurality of punches, punch controllers to operate said punches in groups, a punch head adapted to move said controllers, a feeding mechanism for the tape comprising a floating lever one end of which acts on one of the set controllers as a stop to determine the extent of feed of the tape, and means on the punch head to engage said floating lever to lock it in position to prevent rebound.

22. In a perforating machine in combination, punches and means for operating the same to perforate a tape, a feeding mechanism for the tape comprising a ratchet wheel, a bell crank pawl pivoted on an arm mounted on the stud of said wheel, a spring for holding said pawl normally in engagement with the wheel, a lever connected to said pawl, and means for actuating said lever to positively disengage the pawl from the wheel to position the former and to effect a positive engagement of the pawl with the wheel on its forward movement.

23. A perforating machine comprising a plurality of punches, punch controllers to operate said punches in groups corresponding to the keyboard characters, a keyboard selector mechanism to set said controllers, said selector mechanism comprising a series of notched bars, T-bars extending transversely of and adapted to be operated in

groups by the notched bars, and connecting bars between said T-bars and the punch controllers.

24. A perforating machine comprising a plurality of punches, punch controllers to operate said punches in groups corresponding to the keyboard characters, a keyboard selector mechanism to set said controllers, said selector mechanism comprising a series of notched bars, T-bars extending transversely of and adapted to be operated in groups by the notched bars, connecting bars between said T-bars and the punch controllers, and means for adjusting said controllers.

25. In a perforating machine in combination, a plurality of punches and controllers therefor, a keyboard selector mechanism for setting said controllers, a paper feeding mechanism comprising a feed wheel, a ratchet wheel connected with said feed wheel, means for turning said ratchet wheel, and thereby said feed wheel variable distances, comprising a setting lever, and means to determine the extent of movement of said lever by the punch controllers.

In testimony whereof I have hereunto signed my name in the presence of two subscribing witnesses.

EDWARD E. KLEINSCHMIDT.

Witnesses:

M. E. McNINCH,
CHARLES S. JONES.
